UNITED STATES PATENT OFFICE.

CLEVELAND GENTRY, OF AZUSA, CALIFORNIA.

TREAD FOR TRACTORS.

Application filed August 24, 1921. Serial No. 495,003.

To all whom it may concern:

Be it known that I, CLEVELAND GENTRY, a citizen of the United States, residing at Azusa, in the county of Los Angeles and 5 State of California, have invented new and useful Improvements in Treads for Tractors, of which the following is a specification.

This invention relates to a tread for tractors.

10 The object is to provide a tread for tractors of the self-laying track type, wherein an endless chain is adapted to be driven around a pair of sprockets and to contact with the surface of the ground, the chain comprising a series of alternate links capable of reversal to present a new surface to the action of the driving wheels when worn. Another object is to reduce the strain on the pivotal means between said links when the 20 chain is in operation.

A further object is to provide the chain with removable and reversible tread plates for contact with the ground, the plates being of any desired width and being readily 25 attached to or detached from the side plates of each of the links.

A full and complete understanding of the invention may be obtained from a consideration of the following detailed description, 30 taken in connection with the accompanying drawings forming a part of this specification; it being understood that while the drawings show a practical form of the invention, the latter is not confined to strict 35 conformity therewith, but may be changed or modified, so long as such changes or modifications mark no material departure from the salient features of the invention, as specifically pointed out in the appended claims.

40 In the drawings, in which similar reference characters designate corresponding parts throughout the several views:

Figure 1 is a plan view of a portion of a chain constructed in accordance with the invention.

Figure 2 is a side elevation of the same.

Figure 3 is a detail perspective view of a side plate of one form of link comprising the chain.

50 Figure 4 is a detail perspective view of one of the removable and renewable semi-circular sleeves used in connection with the structure shown in Figure 3.

Figure 5 is a horizontal sectional view

taken through the structure as shown in 55 Figure 1.

Figure 6 is a transverse sectional view taken on the line 6—6 of Figure 1.

Figure 7 is a similar view taken on the line 7—7 of Figure 1. 60

Figure 8 is a detail perspective view of the alternate link.

Referring to the drawings, and particularly Figures 1 and 5; the tread chain comprises two forms of links arranged alternately and each having the same length between the pivotal points, one form of link comprising spaced sides, integrally joined adjacent their ends by hollow sleeves and forming a single casting, while the other link comprises separate side plates adapted to overlap and abut against the outer faces of the sides of the first-named link, and having semi-circular lugs extending half-way across the width of the link and coacting 70 with separate, semi-circular sleeves to form bearing members which traverse the hollow sleeves of the first link, and swivel therein when the chain is travelling around the driving sprockets, tie-bolts passing 75 through the coacting lugs and semi-circular sleeves to bind the two links together while permitting them to rotate freely.

The link composed of two separate members comprises the longitudinally disposed 85 side plates 1, formed of suitable cast metal of great strength and durability, and somewhat elongated as viewed from the side, as shown in Figures 2 and 3, and having their ends semi-circular in form. At the centers 90 from which said rounded ends are struck, the plates 1 are provided with apertures or bolt-openings 2, and the outermost halves of said openings extend longitudinally 95 through opposite, semi-cylindrical lugs 3 formed integrally with the plates 1, and concentric to the openings 2, and extending at right angles to the plates, in a horizontal plane toward the opposite side of the chain, where the free ends of the opposed lugs 100 abut each other at each end of the opposite plates 1. The abutting ends of the semi-cylindrical lugs are located at the center or median line of the chain and serve to hold the side plates 1 in their proper spaced relation after the chain is assembled.

Semi-cylindrical sleeves 4 of a radius equal to that of the lugs 3, are adapted to

coact with the latter to form continuous sleeves extending transversely between the side plates, the said semi-sleeves 4 being of a length to snugly fit between the said plates with the legs in abutting relation, and having semi-bores 2^a co-inciding with the openings 2 of the side plates and the legs, to form continuous bolt openings from the outside surface of one plate to the outside surface of the opposite plate.

At their top and bottom edges, the plates 1 are provided with inwardly directed flanges 5 extending from one lug 3 to the other, and having their outer faces flush with the upper and lower edges of the said plates, thus serving, not only to strengthen and stiffen the plates and provide increased bearing surface for the attachment of tread plates 6, but form a substantial track for the driving sprockets (not shown) when the links are reversed. The tread plates are formed of heavy sheet steel, and are of a width substantially equal to the distance between the centers of the openings 2 of the side plates, and of a length somewhat greater than the width of the chain or the distance between the outside faces of said plates.

The tread plates 6 are attached to the side plates 1 by means of metal brackets having upstanding walls 7 provided with a central opening in registering relation to a similar opening formed in the plate 1, for the passage of a bolt 8, and the said bracket includes a foot-plate 9, provided near its ends with suitable openings in registration with similar openings formed in the tread plates 6, for the passage of bolts 10 having their heads arranged beneath the plates in a position to engage with the ground, the nuts of the bolts 10 bearing against the foot plates 9 of the brackets to securely bind the tread plates to the link, in connection with the bolts 8.

The aforesaid plates 1, together with their lugs 3 and semi-sleeves 4, when properly applied to each other, and having the tread plates 6 attached in the manner described, comprise one link or unit of the completed chain, and this form of link occurs alternately throughout the length of the latter.

The other link or unit comprises an integral casting including spaced side walls 11 adapted to snugly fit between the side walls or plates 1 of the first described link, and joined adjacent to their ends with integral sleeves 12, of an internal diameter to receive the parts 3 and 4 of the same, the centers of said sleeves 12, being the same distance apart as the centers between the latter.

The ends of the side walls 11 are semi-circular in form, and the upper and lower edges of the same are provided with outstanding flanges 13, formed integrally therewith and extending throughout the major portion 65 thereof between the sleeves 12, but on the

outside face of the walls 11 to provide a substantial bearing surface for the truck wheels which run on the track provided thereby and sustain the entire weight of the tractor, in the usual manner.

Metal brackets comprising upstanding attaching plates 15 and integral foot plates 16, are used to secure the treads 14 to the links under consideration, the plates 15 being suitably apertured to register with an opening formed in each side plate or wall 11, for the passage of a bolt 17, and the foot plates having similar apertures in registration with openings in the tread 14 for the reception of bolts 18, the said foot plates being further provided with right angle bends 19 to accommodate the lowermost flanges 13, as clearly shown in Figure 7 of the drawing.

A hardened steel, semi-circular shim 20 is inserted in that half of each sleeve 12 toward the adjacent end of the link, a suitable seat being provided for the purpose so that the inner semi-circular faces of the said shims are flush with the interior of the remainder of the sleeves 12, for the purpose of taking the wear of the parts when the chain is under strain, and the same may be readily replaced when necessary. A tie bolt 21 is passed through the passageway formed by the openings 2, 2^a and 3, respectively, and is equipped with the nut 22 bearing against one outside wall of the adjacent side plate 1, the head of the bolt bearing against the opposite outer face of the other side plate 1.

In assembling the chain, the link composed of the solid casting having the sleeves 12, is placed over the lugs 3 of two adjacent side plates 1, the said lugs passing half-way through the said sleeves and located against the opposed inner walls of said sleeves. The semi-tubular sleeve sections 4 are then introduced in the remaining space within the sleeves 12 and bear against the shims 20 in the latter when the lugs 3 of the other side plate 1 are then inserted in the sleeves with their ends abutting against the ends of the opposite lugs, after which the bolts 21 are applied, and the nuts 23 threaded on the same to be bound tightly in position to prevent the separation of the side plates 1. It will be seen that no friction is created thereby between the two links which must rotate freely about the axis of the bolt, as the strain of the nut is imparted to the abutting ends of the lugs 3.

The tread plates 6 and 14 may then be readily applied to the links by means of their respective brackets, and the same, when become worn or damaged by contact with the ground, may be easily reversed or renewed by simply removing the various bolts from the side walls or plates of the links and from the foot plates of the brackets.

The inwardly directed flanges 5 of the side plates 1, as clearly shown in Figure 1 of the drawing, are in longitudinal alinement with the outwardly directed flanges 13 of the side walls 11 of the other link, and thus a continuous track or bearing surface is provided for the attachment of the tread plates on one side of the several links, and for bearing against the periphery of a sprocket wheel (not shown) during the travel of the chain about the same.

During the operation of a chain of this character for the purpose of driving a tractor or for other heavy duty purposes, the portion of the chain coming in contact with the surface of the driving wheel and the teeth or projections thereon, is subjected to great strain and wear and, when ordinary chains are used, it requires frequent repair or replacement of the chain, but when the present chain becomes worn in this manner, it is only necessary to remove the same from the wheels, and by detaching the tread plates and brackets, the same may be secured to the several links at the worn sides or edges thereof, when practically a new chain is provided. When the links are thus turned upside down to present a new and unworn track to the periphery of the driving sprockets and to the flanged truck wheels (not shown) of the tractor, the several links may also be turned end to end when a new and unworn side of each sleeve 12 will be presented to take the wear of the sprocket teeth, as will be understood.

The strain of the pull of the chain is taken up by the solid sleeve 12 in surrounding relation to the lugs 3 and semi-sleeve 4, thus relieving the strain on the relatively small bolt 21, whose duty is merely to prevent any lateral separation of the side plates 1, and since it is possible to easily and quickly renew the shim 20, it will be seen that the connection between the links is such as to reduce the wear to the minimum. The flanges 5 and 13 may be omitted from the links when the chain is to be used for other than traction purposes.

The outstanding features of the present invention may be said to reside principally in the following vital points—the double flange or rail which, by turning the links upside down permits a new and unworn track to be presented to take the wear of the tractor supporting truck wheels—the solid, one-piece construction of the alternate links having the integral sleeves which may not become detached from their respective side plates and which, by reversing the links, end for end, presents an unworn portion to the driving teeth of the sprockets, the interchangeability and reversibility of the separate side plates having the semi-sleeves extending across half the width of the chain

and the renewability of the semi-sleeves co-acting therewith together with the shims.

From the foregoing it will be seen that a simple and economical drive chain for tractors, or for other heavy duty, has been provided which has means for connecting the links together in a manner to practically eliminate the wear thereof, and that the chain may be reversed with relation to the drive sprockets so as to present an entire new bearing surface to the same, and that the tread plates may be readily reversed when worn, or replaced entirely, without dismantling the chain or requiring the same to be removed from the said drive wheels.

What is claimed is:—

1. In a device of the character described, a chain composed of alternate links interfitting and connected to each other, every other link composed of a single integral casting having spaced elongated side walls connected near their ends by transverse sleeves, the other alternate links comprising separate side plates adapted to bear against the outer side faces of the first link, transverse, semi-tubular lugs carried by said plates and extending halfway through the said sleeves and abutting against each other, a semi-tubular member equal in length to the two abutting lugs adapted to fit in the remaining half of the sleeve to bridge the joint between the lugs and to coact therewith to form a pintle for the sleeve, and means for connecting the separate side plates of the second-mentioned links.

2. In a device of the character described, a chain composed of alternate links interfitting and connected to each other, every other link composed of a single integral casting having spaced elongated side walls connected near their ends by transverse sleeves having interior, removable, semi-tubular shims therein, the other alternate links comprising separate side plates adapted to bear against the outer side faces of the first link, transverse, semi-tubular lugs carried by said plates and extending halfway through the said sleeves and abutting against each other, a semi-tubular member equal in length to the two abutting lugs adapted to fit in the remaining half of the sleeve to bridge the joint between the lugs and to coact therewith to form a pintle for the sleeve, and tie-bolts traversing the passage formed by the lugs and the semi-tubular member and adapted to hold the separate, outer side plates in spaced relation to permit the links to swivel upon each other.

3. A tread for tractors comprising a chain having alternate integral and separable links, the former comprising spaced side walls joined near their ends by integral transverse sleeves, the latter comprising side

plates each having spaced semi-tubular lugs adapted to extend halfway through the sleeves of the integral link, semi-tubular sleeves coacting with the opposite, abutting lugs within said sleeves, and transverse bolts traversing the opening between the opposite lugs and the coacting semi-tubular sleeves for holding the inner ends of the lugs in abutting relation to permit one link to 10 swivel on the other.

4. A chain of the class described composed of alternate integral and separable links, the former comprising spaced side walls joined near their ends by integral transverse sleeves open at each end, each of the separable links comprising a pair of side plates having at each end a pair of opposed lugs, a sleeve segment cooperating with the pair of lugs to form a sectional sleeve inside the 15 integral sleeve, and a transverse bolt extend-

ing through each of the sectional sleeves and cooperating with the integral sleeve to hold the sectional sleeve in assembled relation therein.

5. In a device of the character described, 25 a chain composed of alternate links of different construction, one of the links being made of a single casting having spaced side walls connected by integral sleeves open at each end, the other links being formed of 30 separate side plates having transverse semi-tubular lugs extending inwardly therefrom and abutting each other, and a semi-tubular sleeve forming with the semi-tubular lugs a complete sleeve to be inserted within the 35 integral sleeve of the other link.

In testimony, that I claim the foregoing as my own I have hereto affixed my signature.

CLEVELAND GENTRY.
